LABELING MACHINE

Carl Holm, Worcester, Mass., assignor to Economic Machinery Company, Worcester, Mass., a corporation of Massachusetts

Application July 19, 1939, Serial No. 285,306

17 Claims. (Cl. 91—51)

The present invention relates to a machine for applying labels to articles such as bottles.

An important feature of the invention is the arrangement for gumming each label—the latter being so presented to the gum applying rollers as to eliminate all possibility of following the roller surface, by adhering to the gum thereon. The machine also provides a novel and compact arrangement of its several instrumentalities, involving the disposal of its label holder between the gum-applying mechanism and the bottle or other article to be labelled.

Other and further objects and advantages of the invention will hereinafter more fully appear from the following description taken in connection with the accompanying drawings, in which—

Fig. 1 is a front elevation of a machine embodying the invention.

Fig. 2 is a side elevation of the machine of Fig. 1.

Fig. 3 is a larger scale fragmentary side elevation of the gumming apparatus.

Fig. 4 is a sectional view substantially along the line 4—4 of Fig. 1, showing the label carrier, as well as the article supporting mechanism.

Figs. 5 and 6 are diagrammatic views illustrating successive portions of the label-gumming operation.

With reference to the drawings, the machine provides spaced sides or uprights 1 and 2, Fig. 1, having journalled in their base portions the main shaft 3, which carries a plurality of cams for controlling the several machine movements, as will hereinafter appear. The shaft 3 is actuated from any suitable source of power, not shown, through a one revolution clutch 4 of conventional construction. The clutch may be operated by a foot treadle, not shown, through any suitable connections.

The principal label-handling instrumentality of the machine is a horizontally reciprocating carrier 5, having suction openings on its under side by which to seize and hold the front or printed face of each label. Said carrier is suitably suspended from an arm 6, projecting from a member 5 which is slidable on a rod 7 and on a guide bar 8, both of which extend horizontally from front to rear of the machine and have their support in brackets 9, 9 secured to the upright 1.

The label supply is a stack 10, contained in and held nearly upright, edgewise, by a box or holder 11, which is adjustably mounted on a suitable bracket 14 secured to the side member 2. To an extension of this bracket is pivoted at 13 a hollow arm 12, whose free end, in the

upper position (Fig. 1) of said arm, is adapted to engage and seize by suction the rear or unprinted face of the outermost or lowermost label of the stack 10, for removal of said label from the stack by the downswing of said arm. Said downswing of the suction picker 12 disposes the label in a substantially horizontal position, in or just below the plane traversed by the under surface of the carrier or label support 5; with the arrival of said carrier just over the so-positioned label, the suction on the picker 12 is released, and the suction on the carrier is applied, thereby transferring the label from the picker to the under surface of the carrier, which then moves, as hereinafter described, to expose the under surface of the label to a glue-applying operation, and then to deposit same on the bottle or other article to be labelled.

For the operation of the suction picker 12, a projecting arm 15 thereof has its outer end pivotally connected to a depending rod 16, whose lower end is pivotally connected to a rocker arm 17, journalled on a horizontal rod or shaft 18. Said arm 17 carries a roller 19 which cooperates with a cam 20 on shaft 3; this cam 20 is of the proper contour to produce the up and down swings of the picker 12 in correctly-timed relation to the movement of the label carrier 5.

The suction opening or openings 21 of the picker 12 communicate by an interior chamber 22 with a suction passage 24 extending the full length of the arm; said passage, by means of a flexible hose 23 or the like, is connected to a valve mechanism 25, having a suitable connection 26 to vacuum. Likewise the several suction openings 21 of carrier 5 communicate by an interior chamber 28 and by a flexible hose connection 29 with said valve mechanism 25. The latter is not here illustrated in detail, since its operation will be understood by those skilled in the art; any suitable valve mechanism may be employed to control, in properly timed relation, the application of suction to and the release of suction from the picker 12 and carrier 5.

After a label has been transferred, as hereinbefore described from the picker 12 to the carrier 5, the latter moves rearwardly (toward the left, Figs. 2 and 4) for the application of adhesive to the label. This adhesive is applied first to one-half of the label as the carrier moves rearwardly, and then to the other half of the label as the carrier moves forwardly. The applicator means may be of any of the usual kinds employed in this art for rendering adhesive one surface of a label but the means herein chosen for specific ex-

ample comprises a pair of parallel adhesive-applying rollers 38 and 31, Fig. 3, supported by the side walls of a box 32, which holds the fluid adhesive, and which is supported by a rocking plate 33. The plate is mounted on a shaft 34 extending between the uprights 1 and 2, and rocking of the box is effected through a rod 35 connected at its upper end by a pin 36 and slot 37 to the bracket, and at its lower end to an arm 38, which, like the arm 11, is journaled on the shaft 18. A 10 follower 39 on the arm 38 cooperates with a cam 39 on the shaft 3, to produce the rocking of box 32 at the proper times.

The rollers 38 and 31 are mounted on shafts 40 and 41 journaled in the opposite side walls of the box 32, and these shafts have interengaging gears 42 and 43, Figs. 1 and 3, positioned outside of the box for assuring a rotation of the two rollers in opposite directions. As shown in Fig. 3, a doctor comb 45 is positioned between the rollers, and has opposed edges engageable with the peripheries of the rollers to control the amount of adhesive carried by the roller surfaces. The gum box 32 supports at each end a scraper 45' of conventional construction, for cooperation with each of the rollers 38 and 31.

For driving the rollers 38 and 31, a shaft 46 is journaled in a bracket 47 mounted on the plate 33, Fig. 1. The shaft 46 has on the end thereof a sprocket 48 connected by a chain 49 to a sprocket 50 on the main drive shaft 3. It will be noted that the rotation of the rollers 38 and 31 is such that the upper surfaces of the rollers move toward each other, as indicated by the arrows, Fig. 3, so that the roller surfaces will be moving in the same direction as the label when either roller is engaged thereby.

The label carrier 5 is moved by a link 51, which connects the carrier to the lower end of an arm 52 journaled on a shaft 53, which in turn extends between the upper ends of the uprights 1 and 2. Integral with the arm 52 is a depending arm 54, the outer end of which is connected by a rod 55 to an arm 56 journaled on the shaft 18. The arm 56 carries a cam follower 57 engageable, as shown in Fig. 1, with a cam 58 on the shaft 3.

As the label carrier 5 moves inwardly of the machine (to the left, Fig. 2), the box 32 is tilted counterclockwise, Fig. 3, to bring the right-hand roller 31 against the under side of the label on the carrier, thereby gumming the right-hand half of the label from its middle portion to its right-hand edge, as shown in Fig. 5. As the carrier reverses, and begins its movement to the right, Fig. 3, the box is rocked clockwise, to bring the left-hand roller 38 against the under side of the label for applying gum or adhesive to the left-hand half of the label, from its middle portion to its left hand edge, as shown in Fig. 6. In this way, there is never any chance for the label, in its contact with either gumming roller, to wrap around or follow the roller surface, since the initial contact in each instance is with the label's middle portion, and never with a leading edge of the label. The carrier continues its movement toward the front of the machine (to the right, Fig. 2) until the carrier is in the label-depositing position, viz., the outer limit of its reciprocal travel.

The bottle *a* or other article to be labelled, is adapted to be positioned on a vertically adjustable support 60, mounted in a member 61 on the upper end of a rod 62 which is vertically slidable

in a guide member 63. The latter is supported on a cross bar 64 extending between the uprights 1 and 2. The member 61 has connected thereto a link 65, the lower end of which is connected to an arm 66 turnable on the shaft 18. This arm 66 has a cam follower 61, Fig. 4, cooperating with a cam 68 on the main shaft 3. The cam is so shaped as to raise the bottle *a* into a position directly beneath and practically flush with the label, as soon as the suction carrier 5 reaches its label-depositing position, so that the adhesive-coated lower surface of the label will contact the bottle, immediately upon the release of the suction exerted on said label by the carrier 5. The bottle *a* is held against undue displacement on its support by the lateral wings 60' thereon, best shown in Fig. 1.

As soon as the label has been released from the suction carrier and applied to the upper side of the bottle, the carrier moves rearwardly (to the left, Figs. 2 and 4), and the label presser 69 positioned above the bottle, moves downwardly, and assures a secure attachment of the label to the bottle. The label presser is carried on a vertically reciprocal bar 70, slideable in a bracket 71, which in turn is secured to a cross bar 72 extending between the uprights 1 and 2. The upper end of the bar 70 has a notch 73 to receive the projecting end of an arm 74 turnable on the same shaft 53 on which the arm 52 is mounted. Integral with the arm 74 is a second arm 75, and the free end of this arm is connected by a rod 76 to an arm 77 turnable on the shaft 18. The arm 77 has a cam follower 78 cooperating with a cam 79 on the shaft 3 by which the label presser is moved. The presser 69, as shown, has a sponge rubber or other resilient pad 80 on the under side thereof, for conforming to the contours of the bottle and for assuring a pressure over the entire surface of the label.

In operation, before the above described rearward movement of carrier 5 takes place, the picker 12 will have swung downwardly, carrying into a horizontal position the next-removed label from the stack 10. Then, as the carrier moves rearwardly, there is a momentary dwell of same over the picker-held label, during which the release of suction by the picker and the application of suction to the carrier procures the transfer of the label to the carrier. Then the carrier's rearward movement is resumed, and the picker 12 moves upwardly into the full line position of Fig. 1, in readiness to remove the next label from the stack.

As the carrier moves toward the rear of the machine, the gumming tray is rocked counterclockwise, Fig. 2, to bring the right-hand gumming roller against the under side of the label, when the rollers and label are substantially in the relative positions of Fig. 5, and thereby applying gum to the right-hand half of the label during the continued movement of the carrier to the left. The movement of the carrier is then reversed, and simultaneously therewith the gumming tray is rocked clockwise, Fig. 2, to bring the left-hand roller into position for engagement with the label, as shown in Fig. 5, thereby applying gum to the left-hand half of the label as the carrier moves toward the front of the machine. The portions of the label to which the adhesive is applied successively by the rollers 38 and 31 are shown in Figs. 5 and 6 respectively by the enclosing brackets in these figures. The carrier then continues its forward movement, until it

is in label-applying position directly over the bottle, in which position it remains long enough for the bottle to be elevated to engage the label, the suction in the carrier being at this time cut off to release the label, and the carrier is then withdrawn to its original label-picking position. As soon as the carrier is withdrawn, the label presser is moved downwardly, and assures a secure attachment of the label to the bottle.

While the carrier is in label-applying position, the picker arm 12, which has been in the raised position of Fig. 1, with the end thereof in engagement with the bottom label in the stack of labels, has suction applied thereto to pick up the bottommost label and transfer it by a downward movement of the arm, to a position directly beneath the position of the carrier when the latter is in label-picking position. All of these machine movements are controlled by the cams on the shaft 3, and thus occur in predetermined relation to each other, the cams being suitably designed to control the machine movements in the proper sequence.

The claims of this application are directed to the structure by which adhesive is applied to the label, together with the mechanism for transferring the label to and from the coating means. A divisional application Serial No. 317,712, filed February 7, 1940, since issued as Patent No. 2,242,974, dated May 20, 1941, incorporates claims directed to the label applying instrumentalities and to the particular arrangement of the several instrumentalities of the machine in their coordination with each other.

Although I have shown my improvements, for purposes of illustration, in connection with a semi-automatic labelling machine wherein the articles to be labelled are manually presented to and withdrawn from labelling position and wherein the adhesive, in the form of gum is applied to the exposed surface of the label by means of rollers, it is obvious that if other forms of adhesive are employed the applicator means will be of appropriate type, it will be understood that my invention is not limited to the particular type of machine or to the particular adhesive applying means herein specifically described by way of example, but it is to be understood as broadly inclusive of any and all types of labeling machine falling within the terms of the appended claims.

I claim:

1. In a labeling machine, a reciprocable label carrier and gumming means for a label on the carrier, said means comprising a pair of rollers, and means for shifting the rollers alternately into a position to engage the label on the carrier.

2. In a labeling machine, a reciprocable label carrier and gumming means for a label on the carrier, said means comprising a pair of rollers, a tank on which said rollers are supported, and means for oscillating said tank for shifting the rollers alternately into a position for engagement with a label on the carrier.

3. In a labeling machine, a reciprocable label carrier and gumming means for a label on the carrier, said means comprising a pair of rollers, and means for shifting the rollers alternately into a position to engage the label on the carrier with one roller engaging the label during movement of the carrier in one direction and the other roller engaging the carrier during its movement in the opposite direction.

4. In a labeling machine, a reciprocable label carrier, gumming means for a label on the car-

rier, said means comprising a pair of rollers and an oscillatory support for said rollers by which the latter are alternately supported for engagement with a label on the carrier, and means for shifting the said oscillatory support when the movement of the carrier is reversed.

5. Gumming mechanism for labeling and like machines, comprising rotary gumming rollers rotating in opposite directions, means for conveying a label, by movements in opposite directions, past said rollers, and means for initially contacting each roller in succession with the approximate middle portion of said label, for gumming first one half and then the other half of said label.

6. In a labeling machine, a reciprocable label carrier, a pair of gumming rollers mounted for oscillation about an axis substantially parallel to the rollers, a support for said rollers and means for oscillating said support for shifting the rollers alternately into a position for engagement with a label on the carrier.

7. In a labeling machine, a reciprocable label carrier, a pair of gumming rollers mounted for oscillation about an axis substantially parallel to the rollers, a support for said rollers, means for oscillating said support for shifting the rollers alternately into a position for engagement with a label on the carrier, and means for moving the carrier in timed relation to the oscillatory movement, whereby one roller engages the label for gumming the rearward half of the label during the carrier's movement in one direction and whereby the other roller engages the remainder of the label during the carrier's movement in the opposite direction.

8. In a labeling machine, a reciprocable label carrier, a pair of gumming rollers mounted for oscillation about an axis substantially parallel to the rollers and beneath the label carrier, a support for said rollers, means for oscillating said support for shifting the rollers alternately into a position for engagement with a label on the underside of the carrier, means for rotating the rollers in opposite directions about their axes, and means for moving the carrier in timed relation to the oscillatory movement whereby one roller with its surface moving in the same direction as the carrier engages the label for gumming a part of the label during the carrier's movement in one direction, and whereby the other roller engages at least a portion of the remainder of the label during the carrier's movement in the opposite direction.

9. In a labeling machine, a reciprocable label carrier, a pair of gumming rollers mounted for oscillation about an axis substantially parallel to the rollers and beneath the label carrier, a support for said rollers, means for oscillating said support for shifting the rollers alternately into a position for engagement with a label on the underside of the carrier, means for rotating the rollers in opposite directions about their axes, and means for moving the carrier in timed relation to the oscillatory movement whereby one roller with its surface moving in the same direction as the carrier engages the label for gumming the rearward half of the label during the carrier's movement in the opposite direction, the surface of said other roller moving in the direction of the carrier's movement during gumming of the remainder of the label.

10. In a labeling machine, a label support operative to hold a label with one surface thereof exposed, means operative to move said support

back and forth along a predetermined path, applicator means for causing said exposed surface to become adhesive, and applicator-actuating means operative to bring the applicator means into effective relation to said exposed surface of the label during each of successive back and forth motions of the support, said applicator-actuating means being so constructed and arranged that a portion only of the surface of the label is caused to become adhesive during each effective operation of the applicator means.

11. In a machine of the class described, label-supporting means operative to support a label with one of its surfaces exposed, applicator means, actuating means operative to cause a relative motion of the support and applicator means back and forth in a direction generally parallel to said exposed surface of the label, and means operative to cause the applicator means to contact the exposed surface of the label at a point intermediate the opposite ends of the label during each of successive relative back and forth movements of the support and said applicator means and to remain in contact with said surface during the completion of each such successive movement.

12. In a machine of the class described, means operative to move a label back and forth along a predetermined path with one surface of the label exposed, means for applying adhesive, and means operative to cause such motion of the adhesive-applying means relative to the movement of the label that during movement of the label in one direction adhesive is applied to that portion only of said exposed surface which lies between approximately the mid-point of the label and its trailing edge, and that during movement of the label in the opposite direction adhesive is applied to the remainder of said exposed surface.

13. In the operation of a label-affixing machine of the kind having a reciprocating label support and gum-applying means, that method which comprises as steps causing gum-applying means first to contact the surface of the label at a point intermediate the ends of the latter as the support moves in one direction and to continue such contact until the support completes its motion in said direction, and then causing gum-applying means to contact the surface of the label at a point intermediate the ends of the latter as the support moves in the opposite direction and to maintain such contact until the support has completed its motion in the latter direction.

14. Method of causing a label to become adhesive by the use of a pair of oppositely rotating applicator rolls which comprises as steps so supporting the label as to leave one surface exposed, bringing one of said rolls into contact with said exposed surface substantially at the mid-portion of the latter, causing relative movement of the label and roll such as to progress the roll toward and beyond one edge of the label, bringing the second roll into contact with the exposed surface of the label substantially at the mid-point of the latter, and causing relative movement of the label and said second roll such as to progress said sec-

ond roll toward and beyond the opposite edge of the label.

15. In a labeling machine, label supporting means operative to hold a label with one surface thereof exposed, applicator means for causing said exposed surface to become adhesive, actuating means including parts operative to cause a relative motion of the support and applicator means back and forth in a direction generally parallel to said exposed surface of the label, said actuating means also including parts operative to bring the applicator means into effective relation to said exposed surface of the label during each of successive back and forth relative motions, said several parts of the actuating means being so coordinated and arranged that the applicator means initiates adhesiveness of the exposed surface of the label at a point intermediate its opposite ends and causes such surface to become adhesive from said point to one of the ends of the label during relative motion of the label and applicator means in one direction and causes the remainder of the exposed surface of the label to become adhesive during the following relative motion of the support and applicator means in the opposite direction.

16. In a labeling machine, a reciprocable label carrier operative to support a label with one surface exposed, and applicator means arranged adjacent to the path of said exposed surface of the label, said applicator means comprising a pair of elements, each, when disposed in effective relation to the label, being operative to cause the exposed surface of the label to become sticky, and shifting means operative to shift said elements, alternately, into effective relation to the exposed surface of the label, said shifting means being so constructed and arranged that one only of said elements moves into and remains in effective relation to the label while the label carrier is moving in one direction only and the other of said elements is moved into effective relation to the label only during movement of the carrier in the opposite direction.

17. In a labeling machine comprising means for moving a label in opposite directions along a predetermined path with one surface of the label exposed, applicator means disposed adjacent to said path, said applicator means comprising a pair of elements, each, when disposed in effective relation to the exposed surface of the label, being operative to cause such surface to become sticky, means operative to shift one only of said elements into effective relation to the mid-portion of the exposed surface of the label and to maintain it in such relation while the label completes its motion in one direction, said shifting means being operative, upon reversal of the movement of the label, to shift the first of said elements out of effective relation to the label and to shift the other of said elements into effective relation to the mid-portion of the exposed surface of the label and to maintain such relation while the label completes its movement in the opposite direction.

CARL HOLM.
